(57) **CLAIM**

The ornamental design for an adjustable ventilation sleeve assembly as shown and described.

DESCRIPTION

FIG. 1 is a front perspective view of an adjustable ventilation sleeve assembly showing the new design.

FIG. 2 is a perspective view of the adjustable ventilation sleeve assembly of FIG. 1 shown disassembled and in a smaller scale;

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a front elevational view of the top sleeve portion of the adjustable ventilation sleeve assembly of FIG. 1.

FIG. 10 is a rear elevational view thereof.

FIG. 11 is a left side elevational view thereof.

FIG. 12 is a right side elevational view thereof.

FIG. 13 is a top plan view thereof.

FIG. 14 is a bottom plan view thereof.

FIG. 15 is a front elevational view of the bottom sleeve portion of the adjustable ventilation sleeve assembly of FIG. 1.

FIG. 16 is a rear elevational view thereof.

FIG. 17 is a top plan view thereof.

FIG. 18 is a bottom plan view thereof.

FIG. 19 is a left side elevational view thereof.

FIG. 20 is a right side elevational view thereof.

FIG. 21 is an enlarged front elevational view of a connector clip part of the adjustable ventilation sleeve assembly of FIG. 1.

FIG. 22 is a rear elevational view thereof.

FIG. 23 is a left side elevational view thereof.

FIG. 24 is a right side elevational view thereof.

FIG. 25 is a top plan view thereof; and,

FIG. 26 is a bottom plan view thereof.

The broken lines shown in the figures illustrate portions of the adjustable ventilation sleeve assembly that form no part of the claimed design.
